UNITED STATES PATENT OFFICE.

HARRY MEAD, OF OAKLAND, CALIFORNIA.

PUMP.

1,262,079.

Specification of Letters Patent.

Patented Apr. 9, 1918.

Application filed January 12, 1916. Serial No. 71,678.

To all whom it may concern:

Be it known that I, HARRY MEAD, a citizen of the United States, residing at Oakland, in the county of Alameda and State of California, have invented new and useful Improvements in Pumps, of which the following is a specification.

This invention relates to a deep well pump particularly intended for use in connection with oil wells.

Most of the crude oil produced to-day is pumped out of comparatively deep wells and generally contains a greater or less quantity of sand and natural gas.

The comparatively slow velocity of a rising column of oil in a well when acted on by a pump permits the sand to settle to the bottom where it gradually clogs up the pump. Similarly any pressure of natural gas causes trouble as it often collects in the pipe between the pump and the surface in the form of big bubbles which compress or expand, as the plunger reciprocates, thus rendering the pump inoperable until the gas has been removed.

The object of the present invention is to overcome these troubles by producing a perfect emulsion of oil, sand and gas and furthermore to provide means for maintaining said emulsion as the oil column rises to the surface. Further objects will hereinafter appear.

The invention consists of the parts and the construction and combination of parts as hereinafter more fully described and claimed, having reference to the accompanying drawings, in which—

Figure 1 is a sectional view of the well casing, showing the application of the invention.

Fig. 2 is an enlarged vertical, longitudinal section through one of the pump rod pistons.

Fig. 3 is a cross section on line 3—3, Fig. 2.

Referring to the drawings in detail, A indicates a well casing; 2 a pump barrel of standard or suitable construction; 3 the plunger operable therein; 4 the pump rod and 5 the discharge pipe through which the oil is elevated by the plunger, and 6 a check or foot valve connected to or secured upon

the lower end of the barrel. The pump rod with connected plunger 3 may be operated in the usual or any suitable manner, any mechanism for this purpose is, therefore, not shown. Secured upon the rod are a plurality of interspaced, superposed piston members 7. These members are secured by the couplings 8 and 9 secured on the rod and each piston is provided with a plurality of ports 10 through which the oil passes on the downward stroke of the rod and through which it is prevented from returning by the provision of a plate check valve 11, the movement of which is limited by a collar 12 formed upon the coupling 8. Each piston check valve and connected couplings are constructed in a similar manner and any suitable number of same may be provided, as shown in Fig. 1.

In actual practice a space from sixty to eighty feet has been found most practical.

The discharge pipe is constructed of ordinary casing, and for the purpose of preventing any friction between the piston 7 and the rough interior of the casing 5, a loose fit has been provided; this is, however, not sufficient to permit any perceptible return or leakage of oil.

The sole object of the present invention is to provide means for maintaining the oil while rising through the discharge pipe so agitated that an emulsion of sand and gas from which the oil is generally more or less mixed is formed. Any settling of the sand toward the bottom or formation of gas bubbles, as previously described is thereby eliminated. This result is accomplished in the present instance by the provision of the foot valve 6 and the plurality of superposed piston members 7.

By referring to Figs. 1 and 2, it will be seen that an upward stroke of the pump rod with connected plunger will cause the oil from the well to enter through the foot valve 6 through the barrel to the pump. The downward movement of the plunger will cause the oil to pass through the upper valve in the plunger into the discharge pipe or casing 5, where it gradually ascends; the velocity generally depending upon the depth of the well. The velocity of the rising oil in deep wells is so slow

that the sand has sufficient time to settle down against the pump, where considerable damage, such as clogging of the pump, the cutting away of the wearing surface, etc., is accomplished, which is, however, prevented in the present instance as emulsion of the oil and sand is formed when the oil passes through the several pistons and check valves shown.

- 10 The ports 10 formed in the several pistons are so small that the velocity of the oil in passing therethrough is increased to such an extent as to form the emulsion desired. The emulsion thus formed, carries the sand and 15 gas in an upward direction but would soon permit it to precipitate unless it is sufficiently agitated at suitable intervals or time limits. This is provided for in the present instance by placing the pistons 7 with checks 11 sufficiently close together to agitate the oil as often as is found necessary.

From the foregoing, it will be seen that the pump, check and foot valve 6 is not only relieved from the high pressure produced by the column of oil, as this is partly supported by the different pistons 7, but that choking up of the pump by sand is similarly prevented, as an emulsion is constantly being produced as the oil passes 30 through the ports in the pistons. In other words, the oil is agitated sufficiently often while rising through the pipe to form an emulsion, thereby preventing a precipitation of sand or formation of gas bubbles.

- 35 While the specific form of piston and check valve has here been shown, the purpose of which is to partly support the column and agitate the oil, I wish it understood that any other form of mechanism 40 capable of producing the results desired may be employed, and that I do not wish to limit myself to the specific structure here shown.

The materials and finish of the several 45 parts of the device are otherwise such as the judgment and experience of the manufacturer may dictate.

Having thus described my invention, what I claim and desire to secure by Letters Patent is—

- 50 1. In combination with a pump barrel and discharge pipe of an oil well, and a plunger and pump rod reciprocating in said barrel and discharge pipe respectively, a series of circular piston members secured at suitable intervals upon the pump rod throughout the greater portion of its length, of a diameter but slightly smaller than the discharge pipe and having ports extending therethrough, and upwardly opening check valves for closing said ports upon the upward movement of the pump rod.

- 60 2. In combination with a pump barrel and discharge pipe of an oil well, and a plunger and pump rod reciprocating in said bar-

rel and discharge pipe respectively, a series of circular piston members secured at suitable intervals upon the pump rod throughout the greater part of its length, of a diameter but slightly smaller than the discharge pipe and having ports extending therethrough, and upwardly opening valves, having substantially flat upper surfaces, for closing said ports upon the upward movement of the pump rod.

70 3. The combination with a well tubing of sucker rods reciprocally mounted within the tubing, of members through which liquid passes carried by the sucker rods, said members being of greater diameter than the sucker rods and of slightly less diameter than the inside diameter of the tubing and valve means for controlling the passage of liquid through said member.

75 4. The combination with a well tubing of sucker rods movable longitudinally in the tubing, of a hollow member mounted upon the sucker rods and being spaced from the inside walls of the tubing, and a check valve to control the passage of liquid through said member.

80 5. A device of the character described, comprising a substantially cylindrical body having in one end a threaded socket for engagement by the sucker rod of a pump and having at the other end a central longitudinally extending stem, said stem comprising portions of unequal diameter and the portion of greatest diameter being adjacent to the body, a washer valve seated on the 90 said portion and movable longitudinally thereon, a seat on the portion of less diameter and fitting against the shoulder formed between the two portions, said seat having an annular series of transverse openings covered by the valve when the valve is in contact with the seat, that portion of the stem beyond the seat being threaded, and a sleeve having its ends internally threaded for engaging the threaded portion of the stem and 100 for engagement by the sucker rod.

105 6. A device of the character described, comprising a body having in one end a socket and having at the other a longitudinally extending central stem, a seat on the 115 stem and provided with a series of transverse openings, a valve seated on the stem and movable toward and from the seat for closing the openings, said seat being fixed and the body having means for limiting the 120 movement of the valve away from the seat, and means engaging the body at the opposite side from the seat for holding the seat in place, and for engagement by the sucker rod.

125 7. A device of the character described, comprising a support, a seat of disk shape mounted on the support and having transverse openings, a washer valve on the support adjacent to the disk and movable to 130

ward and from the disk for closing the openings, and means on the support for limiting the movement of the valve away from the seat, said support having means at its ends for engagement by the sucker rod to permit the support to be inserted in the length of the rod.

In testimony whereof I have hereunto set my hand in the presence of two subscribing witnesses.

HARRY MEAD.
